UNITED STATES PATENT OFFICE.

ANDREW J. KELLEY, OF MOUNT VERNON, NEW YORK, ASSIGNOR TO H. & C. BOTTLE MANUFACTURING CO., OF NEW YORK, N. Y., A CORPORATION OF NEW YORK.

DESIGN FOR A VACUUM-INSULATED BOTTLE.

No. 39,857.

Specification for Design.

Patented March 2, 1909.

Application filed December 24, 1908. Serial No. 469,172. Term of patent 14 years.

To all whom it may concern:

Be it known that I, ANDREW J. KELLEY, a citizen of the United States, residing at Mount Vernon, Westchester county, State of New York, have invented a new, original, and ornamental Design for Vacuum-Insulated Bottles, of which the following is a specification, reference being had to the accompanying drawing, forming part thereof.

The figure is a perspective view of a vacuum insulated bottle, showing my new design.

I claim:

The ornamental design for a vacuum insulated bottle, as shown.

ANDREW J. KELLEY.
